SILK SCREEN PRINTING MACHINE

Eugene Landesman, University City, Mo., assignor to
Lawson Printing Machine Co., Inc., St. Louis, Mo.

Filed Apr. 25, 1974, Ser. No. 464,048

Term of patent 14 years

Int. Cl. D18—02
U.S. Cl. D64—11 R

FIG. 1

FIG. 2

FIG. 3

FIG. 4

FIG. 5

FIG. 1 is a front elevational view of the silk screen printing machine showing my new design.

FIG. 2 is a side elevational view as viewed from the left-hand side of FIG. 1.

FIG. 3 is a rear elevational view.

FIG. 4 is a top plan view.

FIG. 5 is a side elevational view taken from the right-hand side of FIG. 1.

I claim:

The ornamental design for a silk screen printing machine, as shown.
